UNITED STATES PATENT OFFICE.

EUGENE L. GREENEWALD, OF WASHINGTON, DISTRICT OF COLUMBIA.

CLOSURE.

1,427,683.

Specification of Letters Patent. Patented Aug. 29, 1922.

Application filed April 5, 1916. Serial No. 89,078.

To all whom it may concern:

Be it known that I, EUGENE L. GREENEWALD, a citizen of the United States, and resident of Washington, District of Columbia, have invented certain new and useful Improvements in Closures, of which the following is a specification.

This invention relates to closures and the method of and machine for making the same, particularly closures for bottles and jars, but it will hereinafter appear that certain features of this invention are not limited to closures but may be embodied in similar devices such as cans.

15 The principal object of my invention is to provide a two-piece threaded closure made from sheet metal and undrawn, as distinguished from those closures made of one piece and drawn from a flat blank. Drawing the metal blanks so as to produce a satisfactory one-piece closure is an expensive operation. The metal in such cases is stretched and it is not practicable to lacquer or decorate the metal in the flat since the 20 drawing would distort the decoration.

Another object of the invention is to form a flanged tubular body in a novel manner, without drawing the metal, and to simultaneously thread the body.

30 Still another object relates to the means whereby the cover part of the closure is secured to the body part.

A further important object is to form an interrupted or mutilated thread or cover 35 engaging means on the body by indenting portions of the body which are only of a single thickness of metal. The body, made from a blank rolled into tubular form and having its coextensive edges secured together, is at least of a double thickness at the 40 seam, where the overlapping edges are soldered or welded together, and where these edges are secured together by an interfolded or lock seam, the overlapping parts are of 45 four thicknesses. My object is to avoid rolling over these thick portions of the body, which strains the screw threading machine and the lacquer or decoration is also marred at the seam.

50 By forming a helical series of inward separate spot indentations or a series of beads on the body having the pitch of the ordinary screw thread on a bottle or jar, I overcome these objections and produce a satisfactory 55 attaching means on the closure. These beads or indentations may be formed in the flat

blank when the same is cut from the sheet or before it is rolled into cylindrical form.

The above and other objects and novel features of my invention will appear from 60 the following description taken with the drawing in which:—

Figure 1 is a view of a closure embodying my invention, partly in side view and partly in section;

65 Figure 2 is a transverse section of the closure on the line 2—2 of Figure 1;

Figures 3 and 4 are plan views of two similar forms of blanks from which may be 70 formed closure bodies;

Figure 5 is a perspective view of a tubular body formed from a flat blank;

75 Figures 6 and 7 are views illustrating the method of flanging and threading the tubular body;

Figure 8 is a sectional view showing a flanged body part with the cover part assembled thereon;

Fig. 9 is a view of another closure embodying my invention.

Referring to the drawing, 15 designates the tubular body part of a closure adapted for use on ketchup bottles, etc. This tubular body is formed from a flat substantially rectangular blank of sheet metal having cut out 85 portions at the ends thereof and if desired may be lacquered or decorated in the flat. The flat blank is rolled into tubular form as shown in Figure 5, the coextensive longitudinal edges of the tubular blank being secured together by an interfolded seam 16 in the usual manner. The adjacent overlapping edges of the tubular blank may also be seamed together by soldering or welding. The seam 16 is disposed wholly within the 90 margin of the tubular body, in other words, the outer surface at the seam or joint is smooth and flush with the outside of the body. As shown in Figure 8, the body is provided with an exterior flange or shoulder 95 100 17 at its upper end, and an outer depression 18 is formed below the flange. The depression 18 is within the margin of the main body portion below it, and the peripheral edge of the flange 17 terminates at or within 105 the marginal outline of the main body portion 15.

In order to form the flange 17 and depression 18 the tubular body *t*, as shown in Figures 6 and 7, is fitted onto the inner 110 mandrel or die *M*, and rests on the surface *m* thereof. The upper end of the mandrel

has an inwardly extending curved seat 21 which is provided with corrugations 22 disposed in planes radial to the axis of the die. Below the seat 21 the die M is provided with 5 a spiral groove 23 which extends downwardly to the surface m. The member M is the bottom half of the interior forming die, the upper half M' resting against the top of the die M, and the members M and M' abutting 10 along the line 24. The die member M' is provided with a seat 25 the surface of which merges into the seat 21. The tube t is fitted over the two members M and M' as shown in Figure 6 and in order to press the thread 15 into the body I provide a member which is made in halves consisting of the parts 26 and 27 which are provided with interrupted ribs 28 on the interior thereof conforming in pitch to the thread 23. The interrupted ribs 20 28 press portions of the tube t into the spiral groove 23 when they move inwardly, but are located so as to only form threads 30 in that portion of the tube which is of a single thickness. I have found that by having the 25 threads interrupted they can be positioned so as not to extend across the side seam 16 which is of two or more thicknesses. This is important since in the manufacture of the closure it is much more difficult to thread on 30 two or more overlapping thicknesses of metal than of a single thickness, and where it is necessary to carry on the operation rapidly, as in an automatic machine, this difficulty is of considerable importance. 35 Moreover in making closures having threads extending across the seam it is necessary to apply considerably more force to the material at the seam and this causes the material at one side of the seam to be raised 40 or projected above one side of the body of the closure. This raised part or projecting edge is troublesome when the cap is applied by capping machines, as the body of the cap is then not a true cylinder. Furthermore the 45 projecting part of the seam is unsightly and when in use the lacquer or coating on the cap quickly wears off at that point and this also renders the cap unsightly. In the closures having side seams it is practically impossible 50 on account of the stiffness and thickness of the overlapped parts at the seam to make a deep thread and this is sometimes desirable. In a closure formed according to my invention, it is possible to make the thread 55 as deep as necessary, since the single thickness of material offers little resistance to the threading operation.

The flange 17 is formed by pressing the tubular body inwardly on the circumference 60 below the upper end a distance substantially equal to the width of the flange. The body is pressed radially inward at this section by a series of separate corrugating devices 65 31 which have noses 32 spaced apart a slight distance all the way around the body sub-

stantially the same distance apart as the corrugations 22 on the seat 21, but staggered with respect thereto so that when the tube is pressed inwardly the metal will be bent and not drawn, since by the corrugating operation the larger diameter is taken up by the corrugations. Simultaneously as the body is forced inwardly by the corrugating members 31 the upper end of the tube above the groove 34 formed by the seats 21 and 25 70 will flow inwardly and finally assumes a position at right angles to the axis of the tube and thus forms a flange at the upper end of the tube with its peripheral edge at or within the margin of the tubular body t. The 75 position of the parts when the members 26 and 27 have been moved in and also when the corrugators 31 have been pressed in is shown in Figure 7. The tube in this position is provided with a flange, and a depression below the flange and is also provided with an interrupted thread and, since the spiral groove 23 on the die M is continuous to the top of the die, the threaded tube t may be screwed off of the die after the top half 90 M' of the die has been raised up out of the way of the flanged end tube.

In Figures 3 and 4 I have shown flat blanks 40 and 41 from which the tubular bodies for the caps are made by rolling the blank into cylindrical form and securing the edges 42 thereof together preferably by an interfolded or locked seam as shown in Figure 2, but a lap or welded seam may also be used. The blank 40 shown in Figure 3 is provided with a series of indentations 45 which extends from the lower edge 43 upwardly at an angle but terminates short of the upper edge 44. The indentations 45 are in a double row and on the proper angle to 100 form a helical interrupted thread on the body when the same is formed into a tube and the edges 42 thereof are locked together. It will be seen that the indentations do not cross the parts of the tube which form the 105 seam. In Figure 4 the indentations 451 are considerably lengthened but the principle is the same as that shown in Figure 3. The indentations can be pressed into the decorated or lacquered blank in the flat in the 110 same operation in which the blank is cut. Therefore when the blank is formed into a tube it is already provided with a suitable thread, and need only be flanged by the arrangement shown in Figs. 6 and 7.

Referring to Figures 1 and 8 in particular the top part 47 consists of a circular disc-like member which may be stamped from sheet material and if desired may be provided with the groove 48 designed to center 125 the top on the body, such groove having a surface or wall engaging or bearing against the inner surface of said body. The flat peripheral edge portion 49 of the top when the body and top are assembled as shown in 130

Figure 8, is bent downwardly into the depression 18 by simultaneously radially corrugating the superposed edges of the flange 17 and the part 49 of the tube. The corrugations 50 formed on the outer surface of the edge portion 49 of the tube register with the corrugations on the body formed by the seat 22 and fingers 31, as shown in Figure 1, and this corrugated edge provides a grip 10 whereby the cap may be readily screwed on and off a container. The top 47 will be held in place since its lower edge 51 extends under the bead or roll 52 formed on the body, both the bead and roll being disposed 15 in a depression 18 and the upper edge of the top part being substantially flush with the body 15. It will be understood that the edge part 49 may be bent in any other manner desired so as to secure the top to the 20 body.

In Fig. 9 I have shown a closure having a tubular body part 15' formed from the blank 40 shown in Fig. 3, the inward indentations 45 provide means adjacent the open 25 end of the closure for coupling it to a container such as a bottle or jar. As shown, the top 47 of the closure may be secured to the body in the same manner as in the closure shown in Fig. 1, or in any other suitable manner.

It is to be understood that while the body is still on the mandrel M the top of the cap may be assembled on the body and secured thereto by a circular series of radial corrugating fingers 63 or other means for bending 35 down into the adjacent depression the contiguous edge portions of the body flange and top, after the top half M' of the mandrel has been moved out of the way. The completed 40 cap can then be readily removed from the mandrel M.

While I have shown and described the invention in detail I do not wish to be limited to the exact forms as illustrated as it will be 45 apparent that various changes may be made in the forms illustrated without departing from the spirit of the invention.

Having thus described the invention what is claimed is:

50 1. A bottle or jar closure comprising a body having a thread at one end consisting of a helically extending series of spot beads, and a cover part secured to the other end of said body.

55 2. A bottle or jar closure comprising a tubular body having a thread adjacent one end consisting of a helically extending row of separate spot indentations, and a cover part secured to and closing the other end of said body.

60 3. A closure comprising a tubular body formed from a sheet metal blank having a row or series of indentations stamped therein and so arranged as to provide a helically 65 extending container-engaging means on the

body when said blank is formed into a tubular body, and a cover part secured to one end of said body.

4. A two-part bottle or jar closure comprising a tubular body having a side seam 70 consisting of overlapped interlocked portions, said body also having a thread at one end thereof consisting of a helically extending row of inward indentations disposed close together but being interrupted at said side seam, and a cover part secured to said body part.

5. A bottle or jar closure comprising a body having a thread at one end comprising a helically extending series of beads, and a 80 separately formed cover part secured to the other end of said body.

6. A closure of the class described comprising a tubular body having an inward depression adjacent its upper end, a cover part 85 secured to and closing the upper end of said body and having a rim portion extending outside said body into said depression, and means adjacent the other end of said body for coupling it to a container.

7. The invention claimed in claim 6 in which the rim portion of said cover part is transversely corrugated.

8. A two-piece bottle or jar closure comprising a tubular body having a side seam 95 consisting of overlapped parts of the blank from which the body is formed, said body also having an inward depression adjacent one end, a cover part secured to and closing said end of the body and having a rim portion 100 extending outside said body into said depression, and an interrupted thread adjacent the other end of said body for coupling the closure to a bottle or jar, said thread being confined to that portion of the body 105 which is only of a single thickness of material.

9. A closure comprising a tubular body having an inwardly extending depression adjacent its upper end, a cover secured to and closing the upper end of said body, said cover having a groove within its margin providing a wall having a surface bearing against the inner surface of said body and also having a rim portion extending outside 110 said body into said depression, and means adjacent the other end of said body for coupling it to a container.

10. A two-piece bottle or jar closure comprising a tubular body having a side seam 120 consisting of overlapped parts of the blank from which the body is formed, said body also having an inwardly extending annular depression in its external surface adjacent its upper end, a cover secured to and closing the 125 upper end of said body, said cover having an annular groove within its margin providing a wall having a surface engaging the inner surface of said body and also having a rim portion disposed outside said body and ex- 130

tending into said depression, and an interrupted thread adjacent the other end of said body for coupling the closure to a bottle or jar, said thread being confined to that portion of the body which is only of a single thickness of material.

11. A blank adapted for use in making bottle and jar closures, such blank comprising a substantially rectangular sheet of metal having cutout portions adjacent opposite ends of one of its longer edges, said sheet also having a row of spaced indentations extending from adjacent the other longer edge and transversely of the blank at an angle to such edges, said indentations forming corresponding beads projecting from one face of said blank arranged to provide a helically extending container-engaging means on the closure formed from or comprising said blank.

12. A blank adapted for use in making bottle and jar closures, such blank comprising a substantially rectangular sheet having a row of spaced spot indentations extending from adjacent one of the longer edges of the blank transversely thereof and at an angle to such edge and arranged to provide a helically extending container-engaging means on the closure comprising said blank.

13. A closure of the class described comprising a tubular body having an inwardly extending depression adjacent its upper end and an exterior shoulder on the body at the upper end of said depression, means on the body for attaching the closure to a container, and a cover part having a rim portion projecting under and attached to said exterior shoulder and disposed within said depression.

14. A bottle or jar closure comprising a tubular body formed from a flat blank having indentations therein and having overlapping parts secured together, a top part formed independently of the body and having its edge extending around the outer side of one end of said body and secured to said body, and an interrupted thread at the other end of said body, said thread being formed by said indentations and confined to that part of the body which is only of a single thickness of metal.

15. A bottle or jar closure comprising a tubular body having a side seam consisting of overlapping parts of the blank from which the body is formed, said body also having an exterior shoulder at its upper end within the marginal outline of said body, a top part formed separately from the body and having its peripheral edge extending outside said body and beneath said shoulder, and an interrupted thread at the lower end of said body, said thread being confined to the part of the body which is only of a single thickness of metal.

16. A bottle or jar closure comprising a

tubular body having a side seam consisting of overlapping parts of the blank from which the body is formed, said body also having an exterior shoulder at its upper end within the marginal outline of said body and a depression in which said shoulder is located, a top part formed separately from the body and having its peripheral edge extending outside said body, into said depression and beneath said shoulder, and means at the lower end of said body for attaching the cap to a container.

17. A bottle or jar closure comprising a tubular body having a side seam consisting of overlapping parts of the blank from which the body is formed, said body also having an exterior shoulder at its upper end, a top part formed separately from the body and having its peripheral edge radially corrugated and extending outside said body and beneath said shoulder, such radial corrugations serving as a gripping surface and an interrupted thread at the lower end of said body, said thread being confined to that part of the body which is only of one thickness of metal.

18. A bottle or jar closure comprising a tubular body having an inwardly extending depression at its upper end and also having an exterior shoulder at the upper end of the depression, a top part having its peripheral edge extending outside said body, beneath said shoulder and into said depression, whereby the margin of said top part will be substantially flush with the main part of the body below said depression, and means at the lower edge of the body for attaching the closure to a container.

19. A bottle or jar closure comprising a tubular body formed from a flat blank and having a side seam consisting of overlapping parts of the blank, said body having an inwardly extending depression at its upper end and also having an outwardly extending shoulder at the upper end of the depression, a top part formed separately from the body and having its peripheral edge radially corrugated and extending outside said body, beneath said shoulder and into said depression whereby the margin of said top will be roughened to provide a grip and will also be substantially flush with the main part of the body below said depression, and an interrupted thread at the lower end of said body, said thread being confined to that part of the body which is only of one thickness of metal.

20. A blank adapted for making a tubular closure body, said blank having a series or row of indentations extending thereacross adapted and arranged to provide helically extending container-engaging means on a tubular body formed from said blank.

21. A stamped flat metal blank adapted for making a tubular closure body, said

blank having a series or row of spot indentations extending from adjacent one edge of the blank at an angle thereto across the blank, said series or row of indentations being adapted and arranged to provide an interrupted container-engaging thread on the body when the blank is formed into a tubular body.

22. A closure of the class described comprising a tubular body having a depression at one end extending inwardly within the outline of the rest of said body, said body also having an exterior shoulder thereon at the upper end of said depression, means on 10 said body whereby the same may be attached to a container, and a cover part having a rim portion projecting under said exterior shoulder, said rim portion having transverse corrugations therein securing the cover 15 part to the body part and also serving as a rough portion whereby the closure may be firmly gripped in attaching it to and detaching it from a container.

23. A blank adapted for use in making 20 closures, such blank having a row of spaced

spot indentations extending angularly from adjacent one edge thereof and arranged to provide a helically extending container-engaging means on the closure formed from or comprising said blank.

30

24. A closure comprising a tubular body having an annular external depression at its upper end, a cover part secured to and closing the upper end of said body and having a rim portion extending around the outside of said body and disposed in said depression, and means adjacent the other end of said body for coupling said closure to a container.

35

25. The invention claimed in claim 24 in which said rim portion is transversely corrugated.

40

26. The invention claimed in claim 24 in which said body and said rim portion have interfitting corrugations.

45

27. The invention claimed in claim 24 in which said coupling means is entirely inside said body.

In testimony whereof I affix my signature.

EUGENE L. GREENEWALD.
